UNITED STATES PATENT OFFICE.

ABRAM C. MOTT, OF PHILADELPHIA, PENNSYLVANIA.

HOT-WATER AND STEAM-BOILER FURNACE.

SPECIFICATION forming part of Letters Patent No. 581,607, dated April 27, 1897.

Application filed October 7, 1896. Serial No. 608,137. (No model.)

To all whom it may concern:

Be it known that I, ABRAM C. MOTT, a citizen of the United States, residing in Philadelphia, Pennsylvania, have invented certain 5 Improvements in Hot-Water and Steam-Boiler Furnaces, of which the following is a specification.

My invention relates to certain improvements in boilers or water-heaters especially 10 adapted for use in heating buildings.

The object of my invention is to arrange the generator in sections so that the sections can be placed side by side and coupled together, each section being directly over the 15 fire-pot and forming the crown and back wall thereof, while the side sections form the sides of the fire-pot and the water-chamber forms the front of the fire-pot.

In the accompanying drawings, Figure 1 is 20 a perspective view of my improved steam-boiler. Fig. 2 is a longitudinal sectional view on the line 2 2, Fig. 4. Fig. 3 is a longitudinal sectional view on the line 3 3, Fig. 4. Fig. 4 is a transverse sectional view on the 25 line 4 4, Fig. 2. Fig. 5 is a perspective view of one of the center sections of the boiler. Fig. 6 is a perspective view of one of the side sections of the boiler, and Fig. 7 is a view of a modification of my invention.

30 A is the base of the boiler-furnace, made up of a series of plates bolted together or made in a single casting. Mounted in suitable bearings in this base are the grate-bars a, geared together by wheels a', and one of the 35 bars has an extension a², by which the grate-bars can be rocked.

The main body of the furnace is made up of the central boiler-sections B and side boiler-sections D. (Shown clearly in Figs. 5 and 6.) 40 These sections when set up in position form the sides and back of the structure, while the front plate E, which extends from one side plate to the other, forms the front of the structure. The sections and front plate are 45 mounted on the base A and secured together in any suitable manner. In the front plate is the fire-door opening e, provided with a door E' and the flue-opening e', provided with a door E². In the base A is an opening c, 50 provided with a door C. Each central section B is made L-shaped, as shown in Fig. 5, the main body of the section extending over the

fire-pot and consisting of the steam-chamber b, web b', and wedge-shaped tongue b². On each side of the web-section are hollow ribs b³ b⁴, which form channels f f' for the products of combustion. The rib b⁴ terminates some distance from the back leg b⁵, forming a passage f², and the rib b³ terminates some distance from the front and forms a passage 55 f³, so that the products of combustion pass from the fire-pot up between the tongues and through the passage f² into the longitudinal passage f and into the connecting-passage f³ to the longitudinal passage f' into the down-take G, and out through the extension G' to the smoke-pipe G². This downtake in the present instance is made of a separate casting bolted to the structure, but may be made an integral part of the structure, as shown in Fig. 7. 60

A valve g may be provided so as to form a direct communication between the downtake and the smoke-stack when it is wished to convey the products of combustion directly to the chimney.

The formation of the central sections in 75 the manner described allows me to provide for the holding in each section of a large quantity of water in a narrow space, which is subjected on each side to the direct action 80 of the products of combustion, and to provide an ample steam-dome. The tongues extending over the fire form long flues for the products of combustion, which pass through the several passages to the smoke-pipe. 85

The sections are coupled together by tie-bolts I I', one passing through the openings b⁶ in the side walls of the steam-chamber, while the other passes through the openings b⁷ in the lower portion of the leg b⁵ of the 90 section. The tie-bolts pass through the end sections D D and are provided with nuts, as shown in Fig. 4. These two bolts hold the sections securely together, and the sections at the openings are preferably ground, so as to 95 form ground-joints, making them water-tight. I preferably mount thin washers of asbestos at the joints, so as to insure a tight fit.

It will be noticed by referring to Figs. 4 and 6 that the inner face of the upper portion of each side section D is of the same contour as the sides of the central sections, only deeper, and that the outside shell d is inclined, with the exception of an offset at

the upper end, which is vertical. The inside shell is also inclined. This enables me to make the upper portion of the combustion-chamber narrower than the lower portion, so that the water in the side sections will be subjected to the direct action of the products of combustion.

The side chambers of the side sections communicate with chambers d^2 at the front and back, so that the combustion-chamber has a water-jacket on three sides, and in the front, directly back of the front plate E, is a water-chamber H, forming what may be termed a "water-front," which communicates with one of the side sections h^2 , as clearly shown in Fig. 6, although in some instances this water-front H may be connected to an independent set of pipes. Thus by this arrangement the fire-pot is entirely surrounded by a water-jacket.

The depending wedge-shaped tongue portions b^2 of the central sections B are inclined, as shown, and preferably rounded in front, so that all the sediment collected in the upper portion of the sections will pass to the rear leg and accumulate in the bottom thereof, which forms the mud-drum, as well as the manifold communicating with the return-tubes. The tongue of each section is rounded in front to give head-room at the fire-door.

It will be seen that the flues f^2 , formed by the ribs of the section, can be readily cleansed through the opening e' in the front of the structure. The soot collected in the upper flue can be dragged to the front and discharged into the lower flue, and the soot of the two flues can then be pushed to the rear and discharged into the fire-pot, so that it will be seen that the flues can be readily cleansed, and the foul matter in the water will be carried to the mud-drum, owing to the peculiar construction of the section.

I provide each central section with an opening at the top, to which can be coupled a steam-outlet pipe J, so that, when required, two or more systems can be coupled to the same boiler. Openings are made in the lower portion of each section, so that the return-tubes of the different systems can be coupled in the same manner, although in some instances one pipe may be used, in which case the other openings are closed by suitable caps or plugs, or a manifold may be mounted above the structure to which the several pipes are connected, and this manifold can be coupled at one or more points to the boiler.

It will be understood that the boiler is provided with suitable gages, regulators, &c., which are common to all structures of this type.

I claim as my invention—

1. The combination of the fire-pot, a boiler mounted above the fire-pot and having a series of narrow depending tongues extending into the combustion-chamber from above and directly over the fire-pot, flues communicating with the spaces between the tongues form-

ing the initial passages to direct the products of combustion to the flues, substantially as described.

2. The combination in a hot-water and steam-boiler furnace, of the fire-pot, a boiler mounted above the fire-pot, extensions of the boiler forming side walls and the back of the fire-pot, flues in the boiler-section, narrow depending tongues extending over the fire-pot and communicating with the top section and the back section of the boiler and forming the initial passages to the flues for the products of combustion, substantially as described.

3. The combination in a steam-boiler furnace, of the fire-pot, the side sections and one or more central sections having depending tongues extending over the fire-pot, and flues formed in the said sections for the products of combustion, the tongues forming initial passages to direct the products of combustion to the flues, substantially as described.

4. The combination in a steam-boiler furnace, of the fire-pot, the side sections and one or more central sections having depending tongues with solid walls extending over the fire-pot, and flues formed by the said sections for the products of combustion, said flues and tongues being at right angles to the front of the furnace, the passages formed by the said tongues being the initial passages for the products of combustion, substantially as described.

5. The combination in a steam-boiler furnace, of the fire-pot, the side sections, central sections, flues formed in the side and central sections for the products of combustion, each central section having a depending tongue extending over the fire-pot, said portion having an inclined bottom, and a leg at the rear forming the back of the combustion-chamber, substantially as and for the purpose set forth.

6. The combination in a steam-boiler furnace, of the side and central sections coupled together forming the boiler and sides and rear of the combustion-chamber, a front plate forming the front of the combustion-chamber, with an independent water-section forming the front wall of the fire-pot and coupled to the boiler proper, substantially as described.

7. The combination in a steam-boiler furnace, of the fire-pot, side and central boiler-sections forming the sides and back of the combustion-chamber, central sections having depending tongues extending over the fire-pot, flues in the said sections for the products of combustion and a down-flue G at the back of the central sections, said down-flue communicating with the stack, substantially as described.

8. A boiler-section having a portion forming the crown of the fire-box and an integral hollow tongue extending down into the combustion-chamber so that when two or more sections are placed side by side the products

of combustion will pass between the tongues to the flues, substantially as described.

9. A steam-boiler section consisting of a casting L-shaped in form having a ribbed body portion and an integral depending tongue adapted to extend over the fire-pot and a back leg connected to the body portion and to the tongue, substantially as described.

10. The combination in a steam-boiler furnace, of the base-section carrying a grate, the hollow side sections and one or more L-shaped central sections communicating with each other and forming the boiler and the combustion-chamber, the central sections having narrow depending tongues extending over the fire-pot, flues formed between each section, the spaces between the tongues communicating with the flues, and the front plate secured to the front of the boiler and forming the front wall of the combustion-chamber, substantially as described.

11. The combination in a steam-boiler furnace, of the base, the hollow side sections and the hollow L-shaped central sections communicating with the side sections, the side

sections being inclined so that the combustion-chamber will be narrower at the top than at the bottom, and a front plate, and flues between the sections communicating with the combustion-chamber, substantially as described.

12. The combination in a steam-boiler furnace, of the fire-pot, the grate, the hollow side sections and L-shaped central sections forming the back and side walls of the fire-pot and combustion-chamber, a front plate having a fire-door, an independent water-front extending back of the front plate and forming the front wall of the fire-pot, the said water-front being independent of the side and central sections of the boiler, substantially as described.

In testimony whereof I have signed my name to this specification in the presence of two subscribing witnesses.
